ECCENTRIC EQUALIZER FOR DERRICKS

Application filed January 23, 1931. Serial No. 510,699.

This invention relates to a derrick construction having a base structure, a crown structure, and a plurality of double leg constructions extended from the base to the crown structure, and means cooperating between the double leg constructions and one of the structures for proportioning the load between the legs of the double leg constructions.

The invention finds its utility in the oil-producing industry where double leg construction derricks are in use. It is the practice at the present time to provide a derrick with a main leg and an auxiliary or removable leg, which removable leg is used during drilling operations when the loads imposed on the derrick are quite heavy and is removed during pumping operations when the load is relatively light. In the present derricks, means is provided for causing the auxiliary leg to take a portion of the load on the derrick, but there is no means for automatically proportioning the load between the main and auxiliary legs. It usually occurs that the main and auxiliary legs do not assume their proper proportions of the load with the result that there is a danger of injury to the derrick.

In the derrick of my invention the equalizing means which I employ automatically proportions the load so that the main leg will take its share of the load, and so that the auxiliary leg will take the remaining share of the load. In designing the derrick of my invention the main leg is made strong enough to safely carry all loads on the derrick during pumping operations in the well. The auxiliary leg is made strong enough to safely carry the difference between the loads imposed on the derrick during pumping and the loads imposed on the derrick during drilling. The equalizing means is so designed that the load will be properly distributed and so that neither leg will be subjected to greater loads than it is intended to support.

The form of equalizing means which constitutes an element of the present combination includes an eccentric equalizing member having eccentric portions engaging the main and auxiliary legs of the derrick, and having fulcrum portions which engage either the

crown structure or base structure, depending on whether the equalizing means is placed in the upper part or the lower part of the derrick.

The equalizing means of my present invention is quite rugged and has ample bearing surfaces for supporting the loads imposed on the derrick.

Other objects and advantages of the invention will be made evident in the following description.

Referring to the drawings in which I illustrate my invention:

Fig. 1 is an elevational view of a derrick incorporating my invention, the central portion of the derrick being broken away and the upper and lower parts moved together in order that the base and crown of the derrick may be illustrated.

Fig. 2 is a cross-section taken on the line 2—2 of Fig. 1.

Fig. 3 is an elevational view showing one of the double leg constructions which constitutes a part of my invention.

Fig. 4 is an enlarged elevational view of the equalizing means.

Fig. 5 is an enlarged elevational view, as indicated by the arrow 5 of Fig. 4.

Fig. 6 is a sectional view taken on the line 6—6 of Fig. 4.

Fig. 7 is a perspective view of the eccentric equalizing member of the invention.

Fig. 8 is a section taken on the line 8—8 of Fig. 3.

Referring to Figs. 1 and 2 of the drawings, the numeral 11 represents a base structure. The numeral 12 represents a crown structure. The numeral 14 represents double leg constructions, and the numeral 15 represents the customary bracings for the derrick. According to usual practice, there are four double leg constructions 14, one of which is arranged in each corner of the derrick. Since each of the double leg constructions is of the same diameter, I will, in describing the details of construction thereof, refer to a single double leg construction. It should be understood, however, that the description applies to all four double leg constructions of the derrick.

Referring to Fig. 3, I will now describe the

100

detailed construction of the double leg construction of the invention. The numeral 16 represents a main leg or primary leg of the derrick. This primary leg 16 is preferably of angular cross-section and is secured at its lower end to a corner piece 17 which constitutes a part of the base structure 11. The upper end of the main leg 16 is secured to an equalizing means 18 which constitutes a part 10 of the present invention and which will be described in detail in the ensuing part of this description. The numeral 20 represents an auxiliary or secondary leg which rests inside the primary leg 16 and is preferably of cylindrical cross-section, as shown best in Fig. 8. The secondary leg is retained in place within the primary leg 16 by suitable tying means 21. The lower end of the secondary leg is provided with a ball 22 which engages a 20 socket 23 provided by the corner piece 17. The upper end of the secondary leg is connected to the equalizing means 18.

Referring now particularly to Figs. 4 to 7 inclusive, I will now describe in detail the equalizing means which, by itself and in combination with the other parts of the derrick, constitutes the present invention. The equalizing means includes an eccentric equalizing member 30 which has a pair of spaced fulcrum portions 31 which are in axial alignment and which are cylindrical, as shown. Interposed between these fulcrum portions 31 is a secondary or central eccentric portion 32 which is arranged on an axis eccentric to the axis on which the fulcrum portions 31 are disposed. The secondary or central eccentric portion 32 is cylindrical, as shown. Arranged outside and adjacent to the fulcrum portions 31 are primary or outer eccentric portions 33 which are relatively spaced but are in axial alignment. The portions 31, 32, and 33 are preferably formed on axes which are relatively offset in one plane but are in alignment in a plane at right angles to the plane in which they are offset.

Secured to the upper end of the primary leg 16 is a primary bearing member 34 having flanges 35 which engage the external faces of the primary leg 16 and through which bolts 36 are extended. Arranged in spaced relation are primary bearings 37 which include block portions 38 formed integral with the primary bearing member 34. Caps 39 are adapted to be secured to the blocks 38 by suitable bolts 40. The primary bearings 37 are in axial alignment and are of such a shape and size that they journal the primary eccentric portions 33 of the eccentric equalizing member 30. Supported at the upper end of 60 the secondary leg 20 is a secondary bearing member 42 having a cylindrical portion 43 adapted to extend inside the secondary leg 20 and having a shoulder 43a with which the upper end of the secondary leg 20 is in engagement. The secondary bearing member

42 provides a secondary bearing which has a block 44 formed as an integral part of the bearing member 42 and a cap 45 which is in the form of a U-shaped strap, and which is secured to the bearing member by suitable bolts 46. These parts are designed to journal the secondary or central eccentric portion 32 of the eccentric equalizing member 30. 70

The crown structure of the derrick includes a head-piece or body 49, one of which is provided in each corner of the derrick, and constitutes a part of the equalizing means provided for each double leg construction. The head-piece 49 provides a flat plate 50 on which the crown structure rests. Depending from the plate 50 is a pair of projections which constitute fulcrum seats 52. The fulcrum seats 52 are in axial alignment and are adapted to be engaged by the fulcrum portions 31 of the eccentric equalizing member 30. Cooperating with the seats 52 are straps 53 secured thereto by bolts 54, which straps extend around and below the fulcrum portions and hold these portions in proper operating relation with the fulcrum seats 52. 80

Extending outward from the primary bearing member 34 is a flange 57 through which a threaded bolt 58 is extended. By rotating the bolt 58 it may be advanced upward or downward and caused to engage or disengage 95 the plate 50 of the head-piece 49.

As shown best in Fig. 6, the eccentric equalizer member is a means for proportioning the load imposed on the primary and secondary legs and has a fulcrum axis X—X 100 around which the member 30 is adapted to fulcrum or swing. The primary leg engages the member 30 on an axis Y—Y, and the secondary leg engages the member 30 on an axis Z—Z. The line Y is spaced from the fulcrum axis X a distance A, and the line Z is spaced away from the fulcrum line X a distance B. If the distances A and B were equal, the load imposed on the primary and secondary legs would be equally divided. It 105 will be seen by changing the design of the member 30 in order to change the distances A and B and to make one greater than the other, that one leg of the double leg construction may be caused to carry a greater portion of the load. 110

The threaded bolt 58 is intended for use when the auxiliary or secondary leg 20 is being installed or removed. At this time the bolt 58 is advanced upward and caused to engage the head-piece 49. The head-piece is thereby moved upward, until the eccentric equalizer member is pivoted around the axis on which the primary eccentric portions 33 are arranged a sufficient distance to raise the secondary or central eccentric portion and the secondary bearing member 42 associated therewith, to accomplish a disengagement between the cylindrical part 43 of the secondary bearing member 42 and the upper end of the 115 120 125 130

secondary leg. When this movement has taken place, the secondary leg may be conveniently removed or placed in operative position. It is of course necessary to remove 5 or place the tying means which holds the primary and secondary legs together. As previously pointed out, the secondary leg is used during drilling operations and when the drilling operations are over the secondary 10 leg is removed in the manner just mentioned. After the secondary leg has been removed, the threaded bolt 58 is moved downward in order that the head-piece 49 and the crown structure may be lowered. If it is desired to entirely 15 remove the strain from the bolt 58, the crown structure may be supported by the primary bearing member 34 in the following manner. By sufficiently lowering the head-pieces 49, the plate 50 thereof will engage upper faces 20 60 of the caps 39. The load is therefore transferred from the crown structure directly to the primary bearing member rather than by means of the eccentric equalizer 30. The secondary bearing member 42 is preferably left 25 in place so that it may be again used whenever desired.

Various modifications might be made in the structure which I have illustrated, and for this reason I do not want to be limited 30 to the details shown. The equalizing means can be placed at the upper end of the derrick shown or can be placed adjacent to the base structure. The eccentric equalizer member might be redesigned, and one of the primary 35 portions 33 and one of the fulcrum portions 31 might be removed. This would leave an eccentric equalizer with but a single fulcrum portion and single primary and secondary portions relatively offset, as will be obvious. 40 If this were done, obviously one of the fulcrum seats 52 and one of the bearings 37 of the primary bearing member would be eliminated. The threaded bolt 58 is not an indispensable part of the invention and may 45 be eliminated if desired. It is quite useful, however, since it provides a simple operative means for permitting an installment or a removal of the secondary leg.

I claim as my invention:

50 1. In a derrick having a crown structure, a base structure, and a double leg construction, the combination of: an equalizing means including an eccentric equalizer having a central eccentric, intermediate fulcrums 55 adapted to engage one of said structures, and outer eccentrics, said eccentrics engaging the legs of said double leg construction.

2. In a derrick the combination of: a base 60 structure; a crown structure; a double leg construction extending from said base to said crown structure; and an eccentric equalizer having a central eccentric means, engaging one leg of said double leg construction, an intermediate fulcrum engaging one of said 65 structures, and outer eccentric means en-

gaging another of the legs of said double leg construction.

3. In a derrick the combination of: a base structure; a crown structure; a double leg construction, including a primary and a secondary leg, extending between said structures; a primary bearing on said primary leg; a secondary bearing on said secondary leg; a pair of fulcrum seats on one of said structures; and an equalizing means having 70 primary and secondary eccentric portions engaging said bearings, and fulcrum portions engaging said fulcrum seats, in such a manner as to proportion the load on said primary and secondary legs. 75

4. In a derrick the combination of: a base structure; a crown structure; a double leg construction, including a primary and a secondary leg, extending between said structures; a pair of spaced and axially aligned 80 primary bearings on said primary leg; a secondary bearing on said secondary leg; a pair of fulcrum seats on one of said structures; and an equalizing means having a pair of relatively spaced primary eccentric portions 85 engaging said primary bearings, a central secondary eccentric portion engaging said secondary bearing, and fulcrum portions engaging said fulcrum seats, in such a manner as to proportion the load on said primary and secondary legs. 90

In testimony whereof, I have hereunto set my hand at Los Angeles, California, this 30th day of December, 1930.
